DETACHABLE CLEAT FOR SHOES

Jack R. Wright, Los Angeles, Calif.

Application November 12, 1946, Serial No. 709,362

3 Claims. (Cl. 36—7.7)

1.

This invention relates to cleats that can be attached to a standard type of shoe for rendering it suitable for use in sports and the like where ordinarily special shoes having integrally formed cleats are employed.

An object of the invention is to provide an inexpensive and practical cleat that can be quickly attached to an ordinary shoe and quickly removed therefrom.

Another object is to provide a detachable cleat that is unusually effective in forming a good engagement with the ground to provide good traction and prevent slipping on sod and the like.

Another object is to provide a detachable cleat for shoes that is adapted for manufacture by cheap and inexpensive methods.

Other more specific objects and features of the invention will become apparent from the detailed description to follow of a preferred embodiment.

In general, a cleat in accordance with the present invention consists of a wire element having four arms that radiate from a common point beneath the sole of a shoe to four points at the edge of the sole where they are turned up and inwardly to engage the edge of the sole. The four arms lie against the face of the shoe sole and, in use, are pressed into the ground to provide a non-skid effect. This non-skid effect can be further increased by providing projections at various points along the arms that will press into the ground even farther.

Referring now to the drawing for a disclosure of certain preferred forms of the invention:

Fig. 1 is a view looking at the bottom of a shoe sole showing a cleat in accordance with the invention attached thereto;

Fig. 2 is a side elevation of the cleat of Fig. 1;

Fig. 3 is a cross section taken in the plane III—III of Fig. 2;

Fig. 4 is a plan view of a modified form of cleat in accordance with the invention; and

Fig. 5 is a detail sectional view taken in the plane V—V of Fig. 4.

Referring first to Fig. 1, a cleat in accordance with the invention may consist of two pieces of wire 10 and 11 respectively, which are interconnected by a sleeve 12. The wire 10 comprises three sections 10a, 10b and 10c, and the wire 11 consists of three sections 11a, 11b and 11c. Each of the sections is substantially straight. The sections 10b and 11b are relatively short and are connected together by the sleeve 12, so that they lie in contact with each other.

2.

The sections 10a and 11a are longer than the sections 10b and 11b and are approximately of equal length. The sections 10c and 11c are both longer than the sections 10a and 11a, and the section 11c is preferably somewhat longer than the section 10c, to better adapt the cleat for use on one or the other of the two shoes of a pair. The particular design shown in Fig. 1 is adapted for use on a left shoe.

At its opposite ends, each of the wires 10 and 11 is turned upwardly and inwardly to form hooks 13 (Fig. 2) which are adapted to extend up past the edge of the sole of the shoe and inwardly against the top of the sole, to retain the cleat in position.

It will be observed from Fig. 1 that the short arms 10a and 11a are extended forwardly, and the hooks 13 on the ends thereof engage the edges of the sole adjacent the tip of the shoe. The other two arms 10c and 11c engage the edges of the sole slightly rearwardly of its widest portion. The longer arm 11c extends to the outer edge of the sole, and the shorter arm 10c extends to the inner edge.

The cleat can be readily attached to the sole by first engaging the hooks on the front arms 10a and 11a over the edge of the sole near its forward end, then engaging the hook on the arm 10c against the inner edge of the sole, and finally bending the arm 11c sufficiently to engage its hook over the outer edge of the sole.

The arms 10a, 11a, 10c, and 11c lying against the underside of the sole provide considerable friction with the earth. This friction can be increased by bending each arm to provide projections that extend further into the ground. In the particular construction shown in Figs. 1 and 2, one projection 15 is shown in each of the shorter arms 10a and 11a, and two projections 16 and 17 are shown in each of the longer arms 10c and 11c. The projections 15 are provided intermediate the ends of the arms 10a and 11a respectively. The projections 16 are provided preferably adjacent the sleeve 12, and the projections 17 are located near the outer ends of the arms 10c and 11c.

As shown in Fig. 3 the sleeve 12 may be formed of sheet metal folded around and enclosing the short sections 10b and 11b of the wires. However it is to be understood that the two wires can be joined by other means. Thus they could be joined by wrapping a wire around them or by welding, brazing, or any other known method of attachment.

There is shown in Fig. 4 a modified construc-

tion of cleat, which differs from that of Fig. 1 in having detachable calks and in having a reinforcing brace interconnecting the long arms.

Thus the cleat of Fig. 4 comprises sections 20a, 20b, 20c, 21a, 21b, and 21c corresponding to the sections 10a, 10b, 10c and 11a, 11b, 11c of Fig. 1, and a connecting sleeve 22 corresponding to sleeve 12 of Fig. 1.

However, instead of having projections formed in the wire itself, as in Fig. 1, the structure of Fig. 4 has threaded holes 23 in the arms for the reception of threaded calks 24 as shown in Fig. 5.

In the structure of Fig. 4, the longest arm 21c is reinforced by a brace 20d. As shown, this brace 20d consists of a continuation of the arm 20c, the hook portion 13 of which is simply bent back upon itself. At its outer end the brace 20d is bent to form an eye 20e which encircles the arm 21c, and the latter is serrated, as indicated at 21d, to resist slippage of the eye 20e therewith.

The brace 20d materially stiffens the long arm 21c and is particularly useful in cleats for large shoes.

The construction shown in Figs. 1 and 2 has the advantage over that shown in Fig. 4 that it can be collapsed for carrying purposes. This is effected by rotating the sections 10b and 11b in opposite directions within the sleeve 12 until the section 10a lies alongside the section 11a, and the section 10c lies alongside the section 11c.

Various other departures from the exact construction shown and described can be made without departing from the invention which is to be limited only to the extent set forth in the appended claims.

I claim:

1. A detachable cleat for a shoe having a projecting sole, said cleat comprising a wire member adapted to lie against said sole, and having a plurality of arms adapted to extend to the edge of the sole, the outer ends of the arms extending first upwardly and then inwardly to engage the edge of the sole and secure the cleat to the sole, said plurality of arms including a pair of rearwardly extending arms one of which is adapted to engage the inner edge of the sole and the other of which is longer than said one arm and is adapted to engage the outer edge of the sole, and a brace extending from the outer end of said one arm to an intermediate point on said other arm.

2. A cleat according to claim 1 in which said brace is rigidly connected to said one arm and slidably connected to said other arm.

3. A cleat according to claim 2 in which said other arm is serrate at the point of engagement therewith of said brace.

JACK R. WRIGHT.
